UNITED STATES PATENT OFFICE.

ARTHUR A. MERRITT, OF WORCESTER, MASSACHUSETTS, ASSIGNOR TO WILLCOX & GIBBS SEWING MACHINE CO., OF NEW YORK, N. Y., A CORPORATION OF NEW YORK.

TREADLE.

1,168,218.

Specification of Letters Patent. Patented Jan. 11, 1916.

Application filed August 4, 1910, Serial No. 575,513. Renewed August 1, 1912. Serial No. 712,773.

To all whom it may concern:

Be it known that I, ARTHUR A. MERRITT, of Worcester, Massachusetts, have invented a new and useful Improvement in Treadles, 5 which invention is fully set forth in the following specification.

This invention relates to locking treadles obviously adapted to various uses, but designed particularly for use in connection 10 with sewing machines. With power driven sewing machines it is customary to provide a pair of treadles for the operator, one to throw the power transmitter into action to drive the machine, and the other to lift the 15 presser-foot. If the presser-foot is lifted while the machine is in operation, or the machine thrown into operation while the presser-foot is lifted, injury to the mechanism is likely to result.

20 In accordance with the present invention locking means are provided adapted to be operated by actuation of either treadle to lock the other treadle against actuation or depression.

25 In the accompanying drawings illustrating embodiments of the invention Figure 1 is an elevation with parts in section showing the application of locking treadles of this invention to a sewing machine; Fig. 2 is a top plan view of the treadles, on a larger 30 scale than Fig. 1, showing the sewing machine in dotted outline; Fig. 3 is an end elevation of the treadle structure; Fig. 4 is a vertical section on line 4—4 of Fig. 3; Fig. 35 5 is an end elevation of another form of treadle structure; Fig. 6 is a section on line 6—6 of Fig. 5, and Fig. 7 is a detail section on the line 7—7 of Fig. 5.

In Fig. 1 the numeral 8 designates a supporting bench or table upon which is mounted 40 a sewing machine 9, shown merely in outline, of the character disclosed in my application for patent Serial No. 467,163, filed December 12, 1908, having a driving pulley 45 10, a rearwardly extending rock-arm 11 (shown in cross-section), a rod 12 having a head on its upper end and depending through an opening at the rear end of arm 11, and a coiled spring 13 about rod 12 and 50 tending to press rock-arm 11 upward. The rock-arm 11 when actuated against the pressure of spring 13 by a downward pull upon rod 12 operates to lift the presser-foot of the machine, which is not shown. There is also 55 shown in Fig. 1 a combined power transmit-

ter and brake mechanism of the character disclosed in patent to Stockton Borton, No. 782,481, dated February 14, 1905, and comprising a driven pulley 14, a driving pulley 15, and a lever 16 for forcing the pulleys 60 into frictional engagement to actuate the driven from the driving pulley. Pulley 14 is connected to the driving-pulley 10 of the machine by a belt 17, and the driving pulley 15 may be connected by a belt 18 to the pulley 19 on driving shaft 20 actuated by any suitable power.

21 is a treadle having a lug or ear 22 connected by a chain, cable, rod or the like 23 to the lower end of the rod 12.

24 is a treadle having an ear or lug 25 connected by a chain or the like 26 with the lever 16 of the power transmitter and brake.

As shown in Figs. 1, 2 and 3, the treadles 21 and 24 are in the form of solid plates; as 75 used in practice, however, they are perforated for lightness, as illustrated in section in Fig. 4. To show such perforations in the other figures would confuse the illustration of other parts.

27 is a treadle frame, the outline of which is shown clearly in Fig. 2, and which is secured to the floor beneath the table 8 by three screws 28.

29, 30 and 31 are lugs or bracket-arms rising from the frame 27. A short shaft 32 is supported at its ends in bearing openings in the upright arms 29 and 30, and passes through lugs on the underside of the treadle 24, which latter is fixed to the shaft by a set 85 screw 33. A similar short shaft 34 is supported at its ends in bearing openings in the upright arms 30 and 31, passes through lugs on the underside of treadle 21, and is fixed 90 to said treadle by a set screw 35.

36 is a plate, web or partition, rising from the frame 27 between the treadles and to a height somewhat above the surface thereof, serving to prevent the operator's foot from being placed upon both treadles at one and the same time; as illustrated this partition is cast integral with the upright arm 30 and extends rearward therefrom, its upper edge being inclined, corresponding to the inclination of the treadles.

37 is a locking bolt, bar or lever pivoted at its middle to swing horizontally on a vertical screw pivot 38, which latter engages at its lower end a screw-threaded socket in frame 27. A flat spring 39, secured at its 105

middle to frame 27 by a screw 40, bears at its ends against stop lugs 42, 42, rising from frame 27, and against depending lugs 41, 41, on locking bolt 37, thereby tending to hold the latter in the normal position in which it is illustrated in the drawings.

43 is a flange, cam-plate or lip depending from the underside of treadle 21, having a straight lower edge 44 and a rear curved or cam-edge 45; 46 is a similar flange, cam-plate or lip depending from treadle 24 having a straight lower edge 48 and a rear curved or cam-edge 47. When treadle 24 is actuated or depressed to throw the power transmitter into action and drive the machine, the cam-edge 47 of its cam 46 acts upon one end of locking bolt 37, swinging the same on its pivot against the tension of spring 39 and carrying the other end of said bolt under the straight edge 44 of the cam 43 of treadle 21, thereby locking the latter treadle against action or depression to lift the presser-foot so long as treadle 24 is depressed. Just the reverse happens when treadle 21 is actuated. It is therefore impossible to lift the presser-foot while the machine is in operation, or to start the sewing-machine while the presser-foot is lifted. Damage, such as is caused by the needle-bar head contacting thread-carrying parts mounted on the presser-foot is thus prevented.

As shown in Figs. 1 and 2, the treadles and their floor-frame are positioned at an oblique angle to the front edge of the work-bench, thus conforming to the operator's position for the type of sewing machine illustrated in outline. For an ordinary sewing machine the treadles would be positioned approximately at right angles to the front edge of the bench.

In the embodiment of the invention shown in Figs. 5, 6 and 7, a longitudinal movable (instead of a pivotally swinging) locking-bolt is employed. One treadle 50 is fixed to its short supporting shaft 51, and has fastened to its inner edge a plate 52 constituting a depending plate, lip or flange adapted upon depression of the treadle to enter a notch or recess 53 in a frame 54. The other treadle 55 has a similar shaft 56 and plate, lip or flange 57, the latter adapted to enter a notch or recess 58 in said frame 54. 59 is a longitudinally movable locking bolt or bar, supported at its ends in bearing openings in bracket-arms or lugs 60 and 62 rising from frame 54, and at its middle passing through an opening in forked bracket-arm or lug 61. 62 is a collar fixed to bolt 59 at its middle by a pin 63 adapted to be put in place by passing it through the openings 64 in arm or lug 61 (see Fig. 6). 65 is a coiled spring encircling bolt 59, and bearing at one end against lug 60 of the frame and at its other end against a washer 66 loose on the

bolt. A similar spring 68 encircles the bolt between lug 62 and another washer 67 loose on bolt. The springs 65 and 68 normally press their washers 66 and 67, respectively, against opposite faces of lug 61 with the collar 62 in the opening of said lug, thereby normally positioning the bolt 59 with its conical ends projecting into the notches 53 and 58 respectively, as shown in Fig. 5. When treadle 50 is depressed, for example, the plate 52 enters notch 53, as shown in Fig. 6, and acts against the conical end of bolt 59, moving it longitudinally against the tension of spring 68 and carrying its other end across the notch 58, in which position it prevents plate 57 from entering said notch, thereby locking treadle 55 against depression. If treadle 55 is first depressed just the reverse happens, the treadle 50, being locked against depression.

I have described my invention with considerable detail for the sake of clearness, but obviously the invention is not limited to the precise construction and arrangement of parts shown, since various modifications thereof may be employed without departing from the spirit of the invention. For example, the invention is applicable not only to two treadles but to three or more.

What I claim is:—

1. The combination of two independently movable treadles, a treadle frame or base on which they are mounted, and locking-means also mounted on said base beneath said treadles and actuated upon operation of either treadle to lock the other treadle.

2. The combination of two independently movable treadles, a treadle frame or base on which they are mounted, a locking-device common to both treadles mounted on said frame beneath the treadles and actuated by the operation of either treadle from a non-locking to a locking position with relation to the other treadle and thereby lock said other treadle against operation.

3. The combination of two independently movable treadles and a pivotal support for the same, a locking-device common to both treadles and positioned beneath the same, and a depending part on each treadle acting upon the operation of either treadle to actuate said locking-device from a non-locking to a locking position with relation to the other treadle and thereby lock said other treadle against operation.

4. The combination of two independently movable treadles, a pivotal support for the same, a locking-device common to both treadles and positioned beneath the same, spring-means for normally holding and returning said locking-device to a non-locking position relative to both treadles, and means associated with each treadle acting upon the operation of either treadle to actuate said locking-device from its non-locking to a

locking position relative to the other treadle and thereby lock said other treadle against operation.

5. The combination of two independently movable treadles, a treadle-frame or base on which said treadles are pivotally mounted, a locking-device common to both treadles and mounted on the base beneath the treadles, spring-means normally holding and
10 returning said locking-device to a non-locking position relative to both treadles, and means associated with each treadle acting

upon the operation of either treadle to actuate said locking-device from its non-locking to a locking position relative to the other 15 treadle and thereby lock said other treadle against operation.

In testimony whereof I have signed this specification in the presence of two subscribing witnesses.
